UNITED STATES PATENT OFFICE.

CLARENCE F. OTT, OF WHITTIER, CALIFORNIA.

RETORT FOR DESTRUCTIVE EVOLUTION AND OXIDATION.

Application filed January 27, 1921. Serial No. 440,477.

To all whom it may concern:

Be it known that I, CLARENCE F. OTT, a citizen of the United States, and a resident of Whittier, in the county of Los Angeles and State of California, have invented a new and useful Retort for Destructive Evolution and Oxidation, of which the following is a specification.

This invention relates to retorts or apparatus used for destructive evolution of volatile elemental constituents of substances and the treatment of same by oxidation processes.

It is the object of my invention to provide a retort wherein these elementals may be separately volatilized at their respective temperatures of vaporization and chemically combined, by passing the same through loosely disposed substances impregnated with oxidizing agents.

This and other objects are attained by the use of constructional features hereinafter specified and shown in the accompanying drawing, which is for illustrative purposes only, and discloses merely the embodiment of my invention.

With reference to the drawing:

Fig. 1. is a view of the apparatus I employ, and is in cross section to better illustrate the interior construction.

Fig. 2. is a plan view of the tray employed to support the upper oxidizing mass.

Fig. 3. is a plan view of the tray employed to support the lower oxidizing mass.

Fig. 4. is a fragmentary sectional detail of the lower portion of the retort shell and taken on line 4—4 of Fig. 1 and looking in the direction of the appended arrows.

Fig. 5. is a fragmentary detail section of charging door.

Fig. 6. is a fragmentary detail section of charging door frame taken in the direction of the arrow 6 in Fig. 5.

Similar characters represent similar parts throughout the several views of the drawing.

This retort is of the type in which the destructive heat is applied externally and acts upon the materials to be volatilized, indirectly, and therefore none of the materials are consumed for the purpose of furnishing heat for the destructive evolution of their elemental constituents.

The shell 11, is provided with a bottom 12, and is preferably of cylindrical construction, and is provided with a removable hood 15 which collects the finished products and

delivers them through the outlet spout 16 to their application of usefulness. The lower rim 17 of the hood 15 is adapted to slidably fit over and confine the upper portion of shell 11.

Although the application and uses to which my invention may be put includes the treatment of all volatile substances, the principal use to which this apparatus is adapted, and the application to which I am confining this presentation is the volatilization of the aqueous liquids obtained in the dry distillation of wood at their respective temperatures, and causing these volatilized liquids to be changed by the addition of other elements, thus conditioning them for the uses to which it is intended they shall be put.

A charge of white oak billets 20, which wood is preferable for my purposes due to its high yield of methyl alcohol, is placed in the volatilizing chamber 21. For use in charging an opening 22 is provided which is so constructed and fitted with a cover 23 as to provide an absolute closure means. The vapors generated from the enclosed charge collect in the volatilizing chamber and are forced by their expansive pressure through the oxidizing mass A which is a granular substance impregnated with an effective oxidizing agent such as potassium permanganate, loosely disposed to allow the free passage of vapors therein and to present a maximum amount of impregnated surface to the vapors passing through. The vapors, in passing through this oxidizing mass A, displace hydrogen atoms with oxygen atoms, of which, in potassium permanganate, the content is very high, and therefore assume a different formation. Acetone, $\text{CH}_3\text{CO.CH}_3$, which volatilizes from white oak at a temperature of 56° C. oxidizes to formic acid, H.CO.OH , and acetic acid, CH_3COOH , in its passage through the oxidizing mass A and passes through the chamber B and the upper oxidizing mass C without further change. With some of the compounds vaporizing at higher temperatures, and which require more extensive contact with the oxidizing agent to complete the transformation, it has become necessary to provide an additional oxidizing mass C, which forms between itself and the mass A an intermediate mixing chamber B in which free oxygen arising from mass A is combined being acted upon. It may be also advisable in the treat-

ment of other basic substances to provide a series of oxidizing masses and intervening mixing chambers.

Within the volatilizing chamber 21 I provide a means of furnishing water vapor to increase the effectiveness of the action of oxidation, by the use of a pan 24 which is annular in formation and sloping to the rear 25 so that the same may be thoroughly 10 drained therewith, and subsequently refilled with fresh water, and is supplied with a capped inlet 26 and a drain cock 27.

The oxidizing mass C is supported upon a tray 30 which comprises an annular side 15 member 31, to which are suitably attached frame members 32 in which is mounted the screen mesh 33 which supports the granular substance forming the oxidizing mass, and admits the free passage of vapors thereinto, 20 and are centrally dipped 34 to increase the area through which said vapors may pass into the oxidizing mass. The annular member 31 is reduced at 35 around its upper edge so that a sealing strip 36 is formed 25 between the same and the shell 11 which is packed with the impregnated granular substance and thus insures the treatment of all vapor passing upward from the chamber B. Grips 38 are provided to facilitate the removal of the tray 30.

Similarly, oxidizing mass A is supported by the tray 40, which comprises an annular member 41 of such a size as will pass through the opening formed by the angle 35 supports 42 for the tray 30, and is supported upon the angle 44 which extends around the interior of the shell 11. Frame members 45 and mounting mesh screen 46 are suitably attached to the annular member 41 and are 40 maintained in their respective positions by the ring members 48 and 49. These frame members 45 are downwardly extended at 50 and upwardly extended at 51, and thereby provide an increased amount of exposed 45 surface through which the vapors may penetrate the oxidizing mass, thus affording a considerable increase in the rate at which the process may be accomplished. A space 60 is formed between the annular member 50 41, which is provided also with grips 38, and the shell 11, and provides a means of sealing by packing with the impregnated granular substance I use.

Heat for the accomplishment of vaporization is furnished from an exterior source such as the burner 65 which directs its flame 66 against the bottom 12. The heat existent

in chamber 21 is registered by a thermometer 70 normally resting in the well 71, supported from the shell 11 by the flange 72. 60 This arrangement facilitates the control of the temperature within the volatilizing chamber. The outer extremity of the closed tube forming the well 70 is flared as at 74 to accommodate a fiber cork 75 which supports and maintains the thermometer 70 in place.

The charging door 22 comprises a circular frame 80 which saddles the exterior of the shell 11, to which it is suitably attached, and a cover 23 is provided with a flange 81 and a centralizing lip 82 which extends into the opening formed by the rim 83. Hooked fingers 85 on the cover 23 are inserted, when it is desired to put on cover, in the notches 86, one of which is illustrated in Fig. 6, and with the revolution of the cover 23 by means of the handle 87 or other suitable means, are caused to mount the incline 84 formed upon the rim 83 of the saddle member 80, thus drawing the cover 23 inwardly and closely confining the gasket 90 between the flange 81 and the rim 83 to form an air-tight closure.

As my invention I claim:

1. In a retort for destructive evolution and oxidation, a closed shell, an upper and lower tray within the shell for receiving therein a granular mass, the said trays being centrally dipped and provided with handle members for removing the same from the shell, and an annular water wall within said shell and inclosing a portion of the lower tray and having an inclined lower end.

2. In a retort for destructive evolution and oxidation, a closed shell, partitions dividing said shell in two compartments and adapted to support a granular mass and allow free passage of gases thereinto, said shell being formed to provide a door in one of said compartments, whereby the same may be charged with material from time to time, a pan within the said shell for maintaining a source of vapor supply, and access to interior of said lastly named compartment whereby thermometric condition of said interior may be gaged.

Signed at Los Angeles, in the county of Los Angeles and State of California, in the presence of two subscribing witnesses, this 18th day of January, 1921.

CLARENCE F. OTT.
